UNITED STATES PATENT OFFICE.

WESLEY TITTLE, OF TOLEDO, OHIO.

REFRIGERATOR.

SPECIFICATION forming part of Letters Patent No. 633,329, dated September 19, 1899.

Application filed April 26, 1899. Serial No. 714,480. (No model.)

To all whom it may concern:

Be it known that I, WESLEY TITTLE, a citizen of the United States, residing at Toledo, Lucas county, Ohio, have invented certain new and useful Improvements in Refrigerators, of which the following is a specification.

In the refrigerators and ice-boxes in common use the ice is stored in the upper part of the device upon open supports through which the air circulates into and out of the cooling-chamber below. When the door of this chamber is opened, the cold air by reason of its greater gravity falls out of the ice-chamber and out through the door. Warm air from the outside now immediately rushes in and takes the place of the displaced cold air, causing the ice to melt rapidly. This waste of ice has to some extent been overcome by providing means for closing the openings in the floor which supports the ice, and special supports have been devised by which communication between the upper and lower chambers can be cut off at will. These devices, however, have not proved entirely satisfactory owing to the fact that it is necessary to operate them manually each time the door is opened and closed. As the operator frequently forgets or neglects to close the bottom of the ice-chamber or to open it he fails to effect the desired saving.

My invention relates to and its object is to provide means for overcoming the difficulties here pointed out and to furnish a mechanism by means of which the ice-chamber shall be automatically and instantly cut off from the refrigerating-chamber when the door is opened and by means of which when the door is closed the air-passages between the upper and lower chambers are immediately opened, thus avoiding the waste due to the cause above indicated. I attain these results by means of the mechanism and arrangement of parts hereinabove described and shown and illustrated in the accompanying drawings, made part hereof, in which—

Figure 1 is a vertical transverse section through a refrigerator, showing above the ice-chamber, below the refrigerating-chamber, and the partition or floor between the two; Fig. 2, a vertical section of a part of the same seen at a right angle to the point of view in Fig. 1, and Fig. 3 an enlarged verti-

cal section of part of my device, as hereinabove described.

Like numerals of reference indicate like parts throughout the drawings.

In the drawings, 1 1 are the side walls of the refrigerator, and 2 the floor. The top is not shown. The space inclosed by the side walls, the top, and the floor is divided into two compartments by horizontal partition 3, the upper compartment forming the ice-receptacle, the lower compartment being for the reception of such articles as are to be kept cold. In one of the walls is the usual door 4. (Indicated in Fig. 2.) For illustration I have shown the horizontal partition 3, constructed after the manner and in the form of a support for ice well known and in common use. I do not, however, limit my invention to the kind of horizontal partition here shown, as it is obvious that my device is equally applicable to any form of open-work ice-support having means for opening and closing communication between the upper and lower chambers.

In the example of my invention illustrated in the drawings 5 5 are a series of horizontal parallel scantlings or bars extending from one wall of the refrigerator to the opposite wall. Alternating with the pieces 5 and arranged in equidistant and parallel relation therewith are troughs 6 6, designed to catch the water of the melted ice, the waste water escaping through down-pipes 6^a. To the upper longitudinal corners of the pieces 5 are hinged, as at 7, wings 8. These wings normally hang vertically against and parallel with the vertical sides of the bars 5, as indicated by the dotted lines in Fig. 3; but the wings may be swung upon their pivots outwardly, so that their lower margins will touch the adjacent troughs. Each of the wings upon corresponding sides of the bars 5 are pivotally connected, as at 9, to a bar 10, running transversely to the wings and beneath the same, while the remaining wings upon the opposite side of each of the bars 5 are in like manner connected with another bar 10, running parallel with the first-mentioned bar 10. The bars 10 are provided with springs 11, which by their tension pull the two bars in opposite directions, thus normally holding the several pairs of wings extended, as shown.

It will be seen that when the wings are extended the spaces between the bars 5 and the troughs 6 are closed and that when the wings are allowed to fall upon their pivots into vertical position against the sides of their respective bars there is left an open space between each of the wings and its neighboring trough.

12 is a lever pivoted, as at 13, near the door, so that when the door is open one end of the 10 lever projects into the opening. From the opposite end of this lever leads a rod 14, which is pivotally secured, as at 15, to a horizontal pulley 16. From opposite sides of this pulley project short radial arms 17. Upon each of 15 the bars 10 is mounted a pair of rollers 18. The radial arms 17 project between the two rollers of each pair, affording a sliding connection between the pulley and the bars 10. The horizontal pulley serves as a double bell-crank 20 lever connected to the two bars 10, the arrangement being such that the movement of the pulley will throw the two bars in opposite directions.

The operation of my device is as follows: 25 When the door 4 is opened, the springs 11, pulling upon their respective bars 10, extend the wings 8, thus cutting off communication between the upper and lower compartments. Now if the door be closed it will come in contact with one extremity of lever 12, causing 30 the other end of the lever to pull on rod 14, which causes the pulley 16 to swing on its axis. This movement of the pulley, through its connections with the bar 10, swings the 35 two bars in opposite directions, overcoming the tension of the springs 11 and causing the several pairs of wings 8 to drop into vertical

position, as indicated by the dotted lines in Fig. 3, thus restoring communication between the two compartments and insuring the circulation of air therebetween. Thus it will be seen that always when the door is opened the bottom of the ice-compartment is instantly and automatically closed and that when the door is closed the bottom of the ice-compartment is instantly and automatically opened.

It will be obvious to those skilled in the art that many forms of connection between the door and the closures for the ice-compartment may be employed, that many devices may be 50 used to retain said closures in normally open or closed position, and that various methods may be employed for controlling said closures by means of the opening or closing of the door. I do not therefore limit my invention 55 to the specific construction and arrangement of parts here indicated.

Having described my invention, what I claim, and desire to secure by Letters Patent, is—

In a refrigerator, an ice-compartment, a floor therefor comprising a series of parallel scantlings or bars, a series of troughs alternating with said bars, and a series of wings pivoted to the sides of said bars and adapted 65 by their movement to open or to close the spaces between the bars and troughs, combined with a door and connections intermediate the door and wings, whereby the wings are actuated by the movement of the door.

WESLEY TITTLE.
